UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A GLASS DISH OR SIMILAR ARTICLE.

45,893.

Specification for Design.

Patented June 2, 1914.

Application filed January 29, 1914. Serial No. 815,310. Term of patent 14 years.

To all whom it may concern:

Be it known that I, ANDREW J. SANFORD, a citizen of the United States, residing at Newark, Ohio, have invented a new, original, and ornamental Design for a Glass Dish or Similar Article, of which the following is a specification, reference being had to the accompanying drawing, forming part thereof.

Figure 1 is a side elevation. Fig. 2 is a

bottom view. Fig. 3 is an end elevation. Fig. 4 a view in cross section of a dish or similar article illustrating my new design.

I claim:

The ornamental design for a glass dish or similar article, substantially as shown.

ANDREW J. SANFORD.
